MECHANICAL STOKER

Friedrick W. Lehnert, New Haven, Conn.

Application April 30, 1932. Serial No. 608,484

2 Claims. (Cl. 110—45)

This invention relates to an improvement in mechanical stokers, that is, devices for feeding fuel to a furnace and removing the ashes therefrom.

5 Mechanically-stoked furnaces use very fine coal and this coal will form lumps or clinkers which, if allowed to pass into the ash-remover, will tend to clog it. The object of this invention is to provide means for turning the lumps or 10 clinkers back onto the fire.

A further object of the invention is to provide for a better distribution of heat from the fire, and the invention consists in the construction as hereinafter described and particularly recited in the 15 claims.

In the accompanying drawing:

Fig. 1 is a side view partly in section of a mechanical stoker constructed in accordance with my invention;

20 Fig. 2 is a plan view of the fire pot showing my guards connected with the shell, the furnace casing being in section;

Fig. 3 is a vertical sectional view, and also showing my improved baffle;

25 Fig. 4 is a perspective view of the guard-plates, detached;

Fig. 5 is a perspective view of my improved attachment for baffle-plates; and

30 Fig. 6 is a perspective view illustrating a baffle-plate provided with my distributing-tubes.

In carrying out my invention, I employ the usual furnace-casing 10 in which a shell 11 is mounted on bearings 12, and these bearings are preferably provided with balls 13. This shell is 35 adapted to be revolved.

Within the shell is the usual fire pot 14 communicating through a passage 15 with a hopper 16 in which coal is placed, and which is moved into the bottom of the hopper by a worm-screw 40 17, operated by an electric motor 20, in the usual manner, the shaft 18 of the screw carrying a gear 19 meshing with teeth formed on the under side of the shell 11 by means of which it is rotated.

On the shell is an outwardly-projecting arm 45 21, which carries ashes onto a screw 22 which conducts them to an ash-receiver.

My improvement consists of two segmental guards 23 and 24 which are mounted upon brackets 25 carried by the shell, and so that the guards 50 revolve with the shell. These guards are adjacent to and extend above the upper end of the shell and preferably are of such a length that a space is formed between them, and the forward ends of the guards with reference to the direction of rotation are bent outward to form arms 26, and so that as the guards revolve with the shell, fine ashes may escape between the ends of the guards or between the guards and the upper edge of the fire pot. Lumps or clinkers will be caught by the 55

arms 26 and forced inward onto the bed of coals in the fire pot, to be disintegrated.

Furnaces of this character are usually provided with a baffle-plate 27 suspended above the fire box and, to distribute the heat, I provide 65 a ring 28 adapted to be clamped to the baffle-plate 27, and this ring is preferably formed in two parts so as to permit it to be clamped to the baffle-plate 27. This ring is formed with a series of openings 29 and in each opening is 70 mounted an upwardly- and inwardly-curved tube 30, through which tubes the heat passes and is generally deflected thereby.

This ring is provided for installation in furnaces already installed, but instead of forming 75 the ring separate from the baffle-plate the baffle-plate may be formed of larger diameter, corresponding to the diameter of the ring 28, as shown in Fig. 6, and the outer edge of this enlarged baffle-plate will be formed with openings 31 80 over which tubes 32 will be arranged, these tubes corresponding to the tubes 30, above referred to.

These guard-plates can be readily produced and attached to shells already installed without great expense, and prevent the clogging of the 85 ash-receiver.

I claim:

1. A mechanical stoker comprising a fire pot, a shell surrounding said fire pot, means for rotating said shell, segmental guards secured to 90 said shell so as to be carried thereby, the segmental guards being circumferentially spaced, and extending from a point below to a substantial distance above the top of the fire pot, whereby, upon rotation, the fine particles of ash pass between said guards and are discharged outwardly 95 of said shell, the guards serving to maintain clinkers and large particles of unconsumed fuel or coke upon the fire bed for further consumption.

2. A mechanical stoker comprising a fire pot, a shell surrounding said fire pot, means for rotating said shell, circumferentially-spaced segmental guards secured to said shell and extending from a point below to a substantial distance above the 105 top of the fire pot, the forward end of each guard with reference to the direction of rotation being curved outwardly, whereby upon rotation of said shell, fine particles of ash may pass between said guards, the curved portions serving to force large 110 chunks of coal and ash back onto the fire bed.

FRIEDRICK W. LEHNERT.
